UNITED STATES PATENT OFFICE.

RICHARD H. COBB, OF CLEVELAND, OHIO.

FUEL-SUPPLY DEVICE.

1,243,818.

Specification of Letters Patent.

Patented Oct. 23, 1917.

Application filed December 16, 1916. Serial No. 137,319.

To all whom it may concern:

Be it known that I, RICHARD H. COBB, a citizen of the United States, residing at Cleveland, in the county of Cuyahoga and State of Ohio, have invented certain new and useful Improvements in Fuel-Supply Devices, of which the following is a specification.

This invention relates to fuel supply devices for internal combustion engines. It has for its principal object to provide means whereby the pressure from the compression stroke and the explosion stroke of an automobile engine is utilized to relieve the vacuum created by the intake stroke of the engine, for causing the fuel to rise to a higher level from the supply tank and then flow by gravity to the carburetor. This is accomplished by simple mechanism, which operates efficiently irrespective of the speed of the engine.

With the above and other objects in view as will be understood, the invention will be hereinafter fully described in connection with the accompanying drawings, which simply illustrate the same, and the novel features thereof will be distinctly pointed out in the appended claims.

In the drawings, like characters of reference indicate corresponding parts.

Figure 1 is a view of an internal combustion engine showing the application of my device, and

Fig. 2 is a sectional elevation of the device. Referring to the drawings, 1 represents an internal combustion engine of any design having a plurality of cylinders indicated by 2. A carburetor of ordinary construction, designated by 3, is connected to the intake 40 of the engine for supplying the proper mixture, and a supply tank 4, for containing gasoline or other liquid fuel, is located in the usual manner below the carburetor.

This invention consists of a reservoir 5, which is provided with a suitable cover 6. Arranged within the reservoir, and depending from the cover is a receptacle 7. From the bottom of this inner receptacle extends an outlet elbow 8, the end of which is inclined and adapted to be normally closed by a flap valve 9. Lugs 10 and 11, on the cover and reservoir respectively, serve to support the same from the dash of an automobile, indicated by 12. The reservoir 5 is provided with a central bottom outlet 13, which is connected to the carburetor 3 by

means of a pipe 14. A conduit 15 connects the fuel supply tank 4 to an inlet valve 16, which is threaded into the cover 6 at 17, and extends within the inner receptacle 7. Said inlet valve is adapted to allow the fuel to flow into the receptacle 7 under certain conditions but will shut off communication therefrom to the supply tank at other times, as will be hereinafter explained. The ball 18 of the inlet valve is held against its seat under proper tension by means of a coiled spring 19, which rests upon an adjusting nut 20 threaded in the inlet valve at 21. This adjusting nut is provided with an opening 22 to permit the fuel to flow into the receptacle 7.

In this invention, a vacuum is created in the receptacle 7 by the intake stroke of the engine, for the purpose of allowing the fuel to flow therein through the inlet valve 16, and pressure from the compression stroke and the explosion stroke relieves this vacuum, thereby permitting the fuel to pass through the outlet elbow 8 into the reservoir 5. Any cylinder of the engine is connected by means of a pipe 23 to a pressure valve 24, which is threaded into the cover 6 at 25 and enters the receptacle 7. This pressure valve is provided with a seat 26 at 85 the upper end of its bore 27 for accommodating a check valve 28. A guide pin 29 depends from the check valve and is encircled by a coiled spring 30, which supports the check valve and rests upon an adjusting nut 31 threaded in the bore 27. An aperture 32 is provided in the nut 31 to permit communication from the pressure valve to the receptacle. Said adjusting nut may be set to any position for causing the spring 30 at 90 to exert the proper tension upon the check valve, so that it will not close too quickly under pressure. A pin 33, arranged above the check valve, limits its movement in that direction. A uniform level of the fuel is 100 maintained in the receptacle 7 by means of a float 34, which is pivotally connected to its side at 35. This float is adapted to rise and fall with the level of the fuel. In moving upwardly, the float forces the shut-off valve 36 against the conical outlet 37 at the lower end of the bore 27, and when the float moves downwardly, said valve falls with it. The shut-off valve is slidably mounted in a bracket 38 fixed to the side of the receptacle. A relief valve 39 is hinged to open outwardly over a hole 40 in the cover 6 to per-

mit the escape of excessive pressure for safety. Air is admitted to the reservoir 5 through a vent 41 in the cover.

Operation: It will be assumed that the 5 piston in the engine cylinder connected to the pressure valve 24 has just completed its exhaust stroke, and that sufficient fuel has flowed from the supply tank 4 through the inlet valve 16 into the receptacle 7 to raise the float 34 until it forces the shut off valve 36 to close the conical outlet 37 of the pressure valve. During the intake stroke, the check valve 28 is forced from its seat by the coiled spring 30. The pressure of the 10 compression stroke and the explosion stroke will force the check valve 28 back to its seat, but not until a certain amount of the pressure, at the beginning of the compression stroke and the explosion stroke, has 15 passed the check valve. This will depend upon the tension of the coiled spring 30. Said pressure will force the shut-off valve 36 away from the conical outlet 37 of the pressure valve and enter the receptacle 7. 20 The ball 18 of the inlet valve 16 will be forced against its seat and thereby prevent the pressure entering the fuel supply tank. Should the pressure in the receptacle be excessive, the relief valve 39 will allow it to 25 escape without causing damage. The pressure, upon entering the receptacle, breaks the vacuum created by the intake stroke, and the fuel flows therefrom through the outlet elbow 8 into the reservoir 5. During 30 the intake stroke, the flap valve 9 will prevent the fuel from the reservoir being drawn up into the receptacle. The above operations are repeated with each intake, compression and explosion stroke of the engine, thereby maintaining a uniform level of the 35 fuel in the reservoir irrespective of the speed of the engine.

Having fully described my invention, what I claim is:

45 1. In a fuel supply device for internal combustion engines, the combination of a reservoir, a receptacle for receiving fuel, a valve for permitting fuel to flow from the receptacle into the reservoir and prevent its 50 return, a conduit establishing communication from a cylinder of the engine to said receptacle, and the conduit including means for admitting pressure from the compression stroke and the explosion stroke of the 55 engine to the receptacle for relieving the vacuum created therein by the intake stroke of the engine, substantially as described.

60 2. In a fuel supply device for internal combustion engines, the combination of a reservoir, a receptacle for receiving fuel, a valve for permitting fuel to flow from the receptacle into the reservoir and prevent its return, an inlet valve for admitting fuel to said receptacle and adapted to be closed under 65 pressure within the receptacle, means estab-

lishing communication from a cylinder of the engine to said receptacle, and said means including a shut-off valve operated from the rise and fall of the fuel in the receptacle, and a check valve adapted to admit pressure from the cylinder of the engine, and then be closed thereby, substantially as described.

70 3. In a fuel supply device for internal combustion engines, the combination of a reservoir, a receptacle for receiving fuel, a valve for permitting fuel to flow from the receptacle into the reservoir and prevent its return, an inlet valve for admitting fuel to said receptacle and adapted to be closed under pressure within the receptacle, means establishing communication from a cylinder of the engine to said receptacle, and means for preventing the sudden closing of said check valve to allow some of said pressure 75 to enter said receptacle, substantially as described.

80 4. In a fuel supply device for internal combustion engines, the combination of a reservoir, a receptacle for receiving fuel, a valve for permitting fuel to flow from the receptacle into the reservoir and prevent its return, an inlet valve for admitting fuel to said receptacle and adapted to be closed under pressure within the receptacle, means establishing communication from a cylinder of the engine to said receptacle, a spring for preventing the sudden closing of said inlet 85 valve, and means for adjusting the tension of the spring, substantially as described.

90 5. In a fuel supply device for internal combustion engines, the combination of a reservoir, a receptacle for receiving fuel, a valve for permitting fuel to flow from the receptacle into the reservoir and prevent its return, an inlet valve for admitting fuel to said receptacle and adapted to be closed under pressure within the receptacle, a pressure valve fitted into said receptacle, means establishing communication from a cylinder of the engine to the pressure valve, the pressure valve having an outlet, a shut-off valve adapted to close the outlet, a float in the receptacle for forcing the shut-off valve closed, and a check valve mounted in the pressure valve adapted to allow a small amount of pressure to pass the same and then be closed by the pressure, substantially as described.

100 6. In a fuel supply device for internal combustion engines, the combination of a reservoir, a receptacle for receiving fuel, the receptacle being arranged within the reservoir and in spaced relation to its bottom and walls, a valve in the bottom of the receptacle 105 for permitting fuel to flow from the receptacle into the reservoir and prevent its return, an inlet valve in the top of the receptacle for admitting fuel thereto and adapted to be closed by air pressure within 110

the receptacle, a pressure valve in the top of the receptacle, means establishing communication from a cylinder of the engine to the pressure valve, the pressure valve having an outlet to the receptacle, a shut-off valve adapted to close the outlet, a float in the receptacle for forcing the shut-off valve closed when there is a predetermined amount of fuel in the receptacle and an air space

above the fuel, a check valve mounted in the pressure valve, a spring tending to keep the check valve open and prevent its sudden closing by the pressure from the compression stroke and the explosion stroke of the engine, and a nut for adjusting the tension of said spring, substantially as described.

In testimony whereof I affix my signature.

RICHARD H. COBB
